UNITED STATES PATENT OFFICE.

WILLIAM HENRY THOMPSON AND IRA FRANKLING CAPE, OF SENECA, SOUTH CAROLINA.

CRANK-SHAFT GEAR FOR LOOMS.

Application filed March 23, 1923. Serial No. 627,061.

To all whom it may concern:

Be it known that we, WILLIAM H. THOMPSON and IRA F. CAPE, citizens of the United States, residing at Seneca, in the county of 5 Oconee and State of South Carolina, have invented certain new and useful Improvements in Crank-Shaft Gears for Looms, of which the following is a specification.

In carrying out the present invention it 10 is our purpose to provide a crank shaft gear for looms that may be bolted to the inside of the fastening pulley or friction plate, this gear being provided with a removable toothed segment that may be removed from the gear when worn and a new segment inserted in its place for thereby overcoming the usual necessity of discarding the entire gear, it being a well established fact that in loom crank shaft gears the 15 wear is always upon a specific portion of the gear.

A further purpose of our invention is the provision of such a gear that is provided with a removable segment which will allow 20 the time of pick on the loom being changed without meshing with the teeth in the main part of the gear.

A further purpose is the provision of such 25 a crank shaft gear that consists of two parts, one of the same being a removable segment containing a certain number of teeth, the main body part of the gear being so constructed as to be easily attached to the inside of the tight pulley or the friction plate of the loom by merely unbolting and removing the usual gear on the loom and bolting in place a gear of the present 30 character.

The nature and advantages of the invention 35 will be better understood when the following detailed description is read in connection with the accompanying drawings, the invention residing in the construction, combination, and arrangement of parts 40 as claimed.

In the drawings forming part of this application, like numerals of reference indicate similar parts in the several views, and wherein:

50 Figure 1 is a front elevation of my improved crank shaft gear for looms;

Figure 2 is a rear elevation thereof; Figure 3 is an end view of the main body portion of the gear; and

Figure 4 is an end elevation of the removable 55 section of the gear.

Referring to the drawings in detail, 5 designates a crank shaft gear substantially similar to the crank shaft gears now upon conventional types of looms with the exception that the same is provided with a cut-out 6. Adapted for position within this cut-out portion of the said gear is a removable segment 7. The gear 5 as well as the removable segment 7 constitutes a rim 65 portion 8 and flange portion 9.

Upon opposite sides of the rim portion 70 of a segment 7 there is formed extension lugs 10 that are adapted for engaging under the side edges of the said opening 6 of the gear for preventing an upward movement 75 of the segment within said opening. The opposite sides of the flange portion 9 of the said segment 7 are also provided with extension plates 11 that are adapted for engagement with the side edges of the flange portion 9 of said gear for preventing a forward sliding movement of the segment with respect to the gear.

The flange portion of the gear and segment 80 are provided with openings 12 for the reception of the usual securing plates after the gear has been positioned upon the loom crank shaft.

It is to be noted that the wear upon the 85 gear is also upon the teeth of the removable segment 7 and after these teeth have become worn to a certain degree it is only necessary that a new segment be inserted within the gear opening which is obviously a great 90 saying in the cost of running looms, it now being necessary to provide a new gear when one or two of the teeth thereof have become worn or broken.

In view of the above description it is 95 believed that the advantages and operation of a crank shaft gear for looms of the present nature will be fully appreciated by those skilled in the art and although we have herein shown and described the preferred embodiment of the present invention, 100 it is nevertheless to be understood that

minor changes may be made therein, without departing from the spirit and scope of the invention as claimed.

Having thus described our invention, what we claim as new and desire to secure by Letters Patent is:

A gear wheel adapted to be applied to the side of a pulley which is fixedly mounted upon the shaft, comprising an arcuate body 10 provided with a central opening adapted to receive the shaft, the body being provided at one side with a recess leading in from the outer edge thereof and communicating with the said opening, the said recess having radially disposed side walls which are disposed at an acute angle with relation to each other and a segment adapted to completely fill the recess and provided with an inner curved edge adapted to conform with

the curvature of the edge of the opening in the body, the segment being provided at its outer side and at its inner portion with lugs adapted to bear against the side surface of the intermediate portion of the body, the body and the segment being provided in the vicinity of their outer edges with outstanding flange sections adapted to register with each other when the segment is in position in the recess the inner surface of the flange upon the body being inwardly inclined and the flange of the segment being provided with lugs adapted to engage under the end portions of the inclined surface of the flange section which is carried by the body.

In testimony whereof we affix our signatures.

WILLIAM HENRY THOMPSON.
IRA FRANKLING CAPE.
